ARRANGEMENT FOR MODULATING
CONTINUOUS WAVES

Maurice Moise Levy and Edward Arthur Rattue,
London, England, assignors, by mesne assignments,
to International Standard Electric Corporation,
New York, N. Y., a corporation of
Delaware.

Application January 5, 1946, Serial No. 639,288
In Great Britain January 15, 1945

13 Claims. (Cl. 250—17)

1

The present invention relates to improvements in arrangements for modulating continuous electric waves, with particular reference to keyed radio telegraph systems.

It is common practice in radio telegraph systems to modulate a continuous high frequency carrier wave with an audible frequency wave or tone, and to interrupt the modulated waves at telegraph speed by means of a suitable key or switch arrangement. It is also generally known that the maximum audio frequency output from a receiver for such a system is produced if the audio frequency waves modulating the carrier waves are of rectangular form, so that the carrier wave is in effect sharply switched on and off. It has been found that best results are obtained when the length of the on periods are approximately 15 times the length of the off periods.

Various arrangements are known for modulating the carrier wave with rectangular waves. Some of these arrangements involve the use of a conventional two-valve multivibrator circuit which generates rectangular switching waves, which are applied to a valve in a carrier frequency oscillator in such manner as periodically to switch the oscillator on and off. The present invention covers a greatly simplified arrangement of this kind in which one of the multivibrator valves is also the oscillating valve which generates the carrier waves. This arrangement saves a valve together with some of the corresponding circuit components which would have to be supplied with the valve.

Accordingly, the invention provides an arrangement for generating modulated electric carrier waves comprising a circuit including a thermionic amplifying valve and adapted to generate regularly-repeated pulses, and an oscillation circuit including the said valve and adapted to generate carrier waves, the said circuits being so disposed that modulation of the carrier waves by the pulses takes place in the said valve.

According to another aspect, the invention provides an arrangement for a radio telegraphy transmitter which includes a multivibrator arranged for generating modulating waves comprising two valves each having an anode, a control grid and a cathode, one of the said valves having an additional anode connected with the control grid and cathode of the same valve in such manner as to generate modulated carrier waves.

The figure of the accompanying drawing shows a schematic circuit diagram of an arrangement according to the invention. It comprises two thermionic amplifying valves 1 and 2, of which the

2

first has two grids 3 and 4 interposed between the cathode 5 and the anode 6. This valve may, for example, be a tetrode of which 3 and 4 are respectively the control grid and the screen grid. If desired this valve may be a pentode with the suppresser grid (not shown) connected to the cathode in the usual way. Valve 2 needs only one grid 7 between the cathode 8 and the anode 9, but this valve could be a tetrode or pentode with the additional grids (not shown) appropriately polarised.

The electrodes 3, 4, 5 of the valve 1 and the electrodes 7, 8, 9 of the valve 2 are connected in a conventional multivibrator circuit, while the electrodes 3, 5, and 6 together form a triode valve connected to an oscillation circuit which generates the high frequency carrier waves. During the operation of the multivibrator, each of the valves is alternately blocked and unblocked, and so the valve 1 can only generate oscillations in those alternate periods of time during which it is unblocked. Thus it will generate equally spaced rectangular pulses of high frequency waves. If the frequency of the multivibrator is within the audible range, the effect is equivalent to modulating the high frequency waves with an audible tone of rectangular wave form.

The screen grid 4, which acts as an anode for the multivibrator, is connected to the grid 7 through a condenser 10, and the anode 9 is connected to the grid 3 through a condenser 11, and through an inductance 12 which acts as a high frequency choke, but which can be disregarded when considering the action of the multivibrator. The grids 7 and 3 are respectively connected to ground through resistance elements 13 and 14.

The electrodes 4 and 9 are connected through resistances 15 and 16 and the normally open contacts of a telegraph key 17 (or equivalent relay or switching device) to the positive terminal of the high tension source 18 for the valves. The negative terminal of this source is connected to earth, and a smoothing network 19 comprising two resistances and a condenser is associated with the key for suppressing switching clicks, according to the usual practice.

The grid 3 and the anode 6 of the valve 1 are connected by a parallel resonant circuit comprising the inductance 20 and condenser 21 which is tuned to the desired carrier frequency. A piezo-electric crystal 22 or other equivalent series resonant circuit or device tuned to the same frequency may be included in series with the grid 3. Anode current is supplied to the anode 6 from ter-

terminal 18 through the key 17 (when operated) and a high frequency choke 23 to a tap on the inductance 20. A blocking condenser 24 is connected in series with the grid 3, to isolate it from the anode potential, and a resistance 25 may also be included to prevent undesired parasitic oscillations. Condensers 26, 27 and 28 are by-pass condensers for the carrier frequency and will be small compared with the multivibrator condensers 10 and 11, so that they will have a negligible susceptance at the pulse repetition frequency. The cathode 5 is connected to earth through a bias network consisting of a resistance 29 and by-pass condenser 30, and the cathode 8 is connected directly to earth. The modulated carrier wave output may be obtained from the terminal 31, and may be supplied to suitable amplifiers or other apparatus (not shown) in any convenient way.

When the key 17 is operated to connect the positive terminal of the high tension source 18 to the valves, the multivibrator operates in the usual way, and the time constants of the coupling networks formed by the elements 10, 13, 15 and 11, 14, 16 should be so chosen that the valve 1 is blocked for a desired fraction of the period, and unblocked for the remainder. For example, the period of the multivibrator could be 1.25 milliseconds, and the time constants could be chosen so that the valve 1 is blocked for .5 millisecond and unblocked for 0.75 millisecond, giving the preferred ratio of 1.5. The constants of the oscillation circuit associated with the anode 6 could be chosen so that the carrier frequency which is generated therein is 500 kilocycles per second, for example.

It will be evident that when the key 17 is operated, an output of the carrier waves modulated by an audible tone at 800 cycles per second, for example, will be obtained at terminal 31, and when the key is released, there will be no output. The tone frequency modulated output may therefore be interrupted according to a telegraph code by means of the key 17 in the usual way.

It will be understood that the multivibrator circuit associated with both the valves and also the oscillation circuit associated with the valve 1 are of conventional types and do not need any more detailed explanation, since their action is well known. The only special points are the choke coil 12 and condensers 27 and 28 which are used to exclude the carrier waves from the multivibrator circuit. These elements should preferably be small enough for their effects on the multivibrator circuit to be negligible. The resistance 29 should be chosen so that the valve 1 is biased so that oscillations start easily when the valve becomes unblocked and the condenser 30 should be large so that the cathode 5 is effectively earthed at the carrier frequency.

It will be understood that each of the cross-coupling network circuits for the multivibrator consists effectively of a series condenser (10 or 11) and two shunt resistances (13, 15 or 14, 16) since the resistances 15 and 16 are effectively earthed through the high tension source for the pulses. The carrier waves are excluded from the multivibrator circuits by shunting the input of one of them by the condenser 28 and the output of the other by the condenser 27, the inductance 12 preventing the carrier waves from being shunted directly to ground through the condenser 27. It is to be noted that the inductance 12 could be replaced by a resistance which, however, would have to be taken into account in considering the

time constant of the corresponding coupling network.

It should also be noted that the functions of the electrodes 4 and 6 of the valve 1 could be interchanged, if desired; in other words the electrode 4 could serve as the anode for the oscillation circuit, and the electrode 6 could serve as the anode for the multivibrator circuit.

What is claimed is:

1. An arrangement for generating modulated electric carrier waves comprising a first and second thermionic amplifying valve each having an output circuit coupled to the input circuit of the other valve through a corresponding reactance-resistance network in such manner as to generate regularly repeated pulses by which the said valves are alternately blocked and unblocked, and an oscillation circuit coupling the input circuit of the first of the said valves to a second output circuit of the same valve to generate pulses of carrier waves during the periods when the said first valve is unblocked.

2. An arrangement according to claim 1, in which the said first valve comprises a cathode electrode, anode electrode, and at least a first and second grid electrode intermediate its anode and cathode electrode, the input circuit of said first valve comprises its cathode electrode and the first grid electrode closest thereto, one output circuit of said first valve comprises its cathode electrode and the second grid electrode and the second output circuit of said first valve comprises its cathode electrode and its anode electrode, said second valve comprising a cathode, anode and grid electrode, the input circuit of said second valve comprises its cathode and grid electrode, and the output circuit of said second valve comprises its anode and cathode electrodes, means for polarizing both of said anode electrodes and said second grid electrode positively with respect to the corresponding cathode electrodes.

3. An arrangement according to claim 2 in which the anode electrode of the first valve is coupled to said oscillation circuit.

4. An arrangement according to claim 3, wherein in one of said reactance-resistance networks comprises a condenser coupling the first grid electrode to the anode electrode of the second valve and a resistance coupling the first grid electrode to ground, the other reactance resistance circuit comprises a condenser coupling the grid electrode of said second valve to the second grid electrode of the first valve, and a resistance coupling said grid electrode of said second valve to ground, the corresponding cathodes being also coupled to ground.

5. An arrangement according to claim 4 in which the oscillation circuit comprises a resonant circuit connecting the anode electrode of the first valve to the first grid electrode and tuned to a frequency high compared with the repetition frequency of the pulses.

6. An arrangement according to claim 5 in which the resonant circuit comprises a parallel resonant circuit.

7. An arrangement according to claim 6 comprising a piezo-electric crystal connected in series with the parallel resonant circuit and said first grid electrode, and tuned to the same frequency.

8. An arrangement according to claim 7 comprising means for excluding the carrier waves from the circuits in which the pulses are generated.

9. An arrangement according to claim 8 in which the said means comprises an inductance

connected between the first grid of the first valve and said one reactance-resistance network, a condenser shunting the input of the said one network and a condenser shunting the output of said other network, the reactance of the inductance and the susceptance of the condensers being negligible at the frequency of repetition of the pulses.

10. An arrangement according to claim 9 in which the time constants of the reactance-resistance networks are so chosen that the repetition frequency of the pulses is within the audible range.

11. An arrangement according to claim 10 in which the said time constants are also so chosen that the length of each unblocking period of the first valve is substantially equal to 1.5 times the length of each blocking period.

12. An arrangement according to claim 11, comprising means for interrupting the modulated carrier waves for signalling purposes.

13. An arrangement according to claim 12 in

which the interrupting means comprises a two-position switch adapted to disconnect the source which provides the electron current for the said valve or valves in one position, and to reconnect the said source in the other position.
